(57) **CLAIM**

The ornamental design for an air freshener housing, as shown and described.

DESCRIPTION

FIG. 1 is a perspective view of a bottle showing an embodiment of our new air freshener housing;

FIG. 2 is a front view of the air freshener housing of FIG. 1;

FIG. 3 is a back view of the air freshener housing of FIG. 1; FIG. 4 is a right side view of the air freshener housing of FIG. 1;

FIG. 5 is a left side view of the air freshener housing of FIG. 1;

FIG. 6 is a top view of the air freshener housing of FIG. 1; and,

FIG. 7 is a bottom view of the air freshener housing of FIG. 1.

The broken-line disclosure shown in FIGS. 1, 4, 5 & 7 is for illustrative purposes only and forms no part of the claimed design.
